SAFETY SHUTOFF DEVICE FOR FURNACES

Michael S. Czolgosz, Gary, Ind., assignor of one-half to Hyman Shanker, Gary, Ind.

Application May 21, 1945, Serial No. 594,910

5 Claims. (Cl. 169—42)

The present invention relates to safety means for closing the dampers in a hot air furnace in the event that the heat becomes too great in the bonnet of the furnace. Hot air furnaces may become dangerous if the fire gets out of control and the temperature in the bonnet rises to such a point that the air would start a fire either in the duct system or at the outlets thereof. Automatic draft controls embodying a thermostat have been used to overcome this danger to a certain extent. However, such devices are not completely reliable because the failure of the electric current will prevent them from functioning. Furthermore, there are many hot air furnaces used where the expensive thermostat and electric motor are not employed.

I am aware that several patented devices have been provided for the purpose of closing the draft door of a hot air furnace when it becomes overheated. Many of these devices are similar to the present device in that they depend upon melting a material having a low melting point to release some mechanical means, and thus permit the draft door to close. My invention, however, differs from these devices in that it provides a means whereby the melting fuse can be positioned at the proper place within the bonnet of the furnace to respond more readily to overheating, and can be replaced immediately without difficulty and without excessive expense to the owner.

It is a purpose of the present invention to provide a safety device for hot air furnaces wherein two control bars are mounted in face to face relation to provide a channel throughout their lengths together with means pivotally supporting each bar intermediate its ends for rotative movement independently of the other bar, and a fusible element in the channel of the bars holding them normally aligned, but allowing them to separate like the blades of a pair of shears when the fusible element melts.

My invention contemplates a safety device of the above character which is readily mountable in the bonnet of a hot air furnace by providing an opening in the bonnet and clamping a mounting mechanism carrying the safety device to the opening. The opening must be situated so that the inner end of the safety device is positioned as nearly as possible over the hottest part of the furnace so that in the case of overheating, the safety device will respond promptly.

It is also a purpose of my invention to provide a safety device comprising two bars, one of which is connected to the damper and the other of which is connected to the damper regulating

means, the bars being pivotally mounted on a common axis between their ends so that if they swing with respect to each other about the common pivot, the connection between the damper and the regulator will be varied as to length. In this combination it is also a purpose of my invention to secure a fusible element by providing a channel between the bars opened at the exterior of the furnace but closed within the furnace when the bars are aligned. This fusible element is maintained in position within the furnace bonnet by the tendency of the two bars to turn with respect to each other, and when the fusible element melts it releases the bars for such turning movement.

The nature and advantages of my invention will appear more fully from the following description and the accompanying drawing wherein a preferred form of the invention is disclosed.

It should be understood, however, that the drawing and description are illustrative only, and that they should not be taken as limiting the invention except insofar as it is limited by the claims.

In the drawing:

Figure 1 is a side view of a hot air furnace to which my invention has been applied. A portion of the bonnet of the furnace is broken away to illustrate the mounting of my safety device.

Figure 2 is an enlarged view of the safety device and its mounting plates showing the open and closed position of the safety device.

Figure 3 is a sectional view taken on the line 3—3 of Figure 2, and

Figure 4 is an enlarged sectional view taken on the line 4—4 of Figure 2.

Referring now to the drawing, the showing in Figure 1 is of an ordinary hot air furnace which comprises a fire box 10, within a shell 11, which terminates in an upper portion 12, which is normally termed the bonnet. The fire box has its air inlet opening at 13, which is controlled by a door 14. The outlet for the products of combustion from the fire box is shown as 15. The hot air used for heating purposes is drawn off from the bonnet 12 through a main duct 16 and distributed in the usual manner by branch ducts.

The damper door 14 is normally controlled by a flexible member 17 that extends upwardly over a pulley 18, and is connected to some means by which the opening of the door can be controlled. In many instances this means may comprise an electric motor that is controlled by a thermostat to pull up on the flexible member 17 when the temperature around the thermostat falls below a certain level and to release the flexible mem-

ber 17 when the temperature around the thermostat gets too hot. These devices are common in the art, and since a detailed showing or description thereof is not necessary to the understanding of my invention, they will not be further described.

My invention comprises a safety device 19 that is interposed in the flexible member 17 in the manner illustrated. The function of the safety device is to lengthen the member 17 and thus allow the door 14 to close in the event the temperature in the bonnet 12 reaches a dangerous height. The safety device 19 comprises two bars 20 and 21, preferably constructed of sheet metal. These two bars have ears 22 and 23 thereon. The ear 22 which is on bar 20 is connected to that portion of the member 17 which extends down to the door 14. The ear 23 on the bar 21 is connected to the upwardly extending portion of the member 17. The two bars 20 and 21 have individual pivot pins 24 and 25 respectively. These pivot pins are located intermediate the ends of the bars and are on the same axis, so that the bars can rotate with respect to each other like the blades of a pair of shears.

In order to mount the device 19 in the proper position, it is necessary to cut an opening 26 in the bonnet 12 through which the bars may extend into the bonnet. Two mounting plates 27 and 28 are mounted on the bonnet 12. One of the plates, that is plate 28, has two raised portions 29 and 30 providing bearings for the pins 24 and 25. It will be noted that the bars have circular projections 31 and 32 thereon, and the mounting plates 27 and 28 are cut out so that they provide just sufficient clearance for the circular portion 31 and 32. This prevents leakage of air in any substantial quantity through the bonnet wall.

The bars 20 and 21 have opposed channels 33 and 34 extending lengthwise thereof, so as to provide a passage from the ends of the bars where the ears 22 and 23 are located throughout the length of the bars. The channels 33 and 34, however, terminate just short of the ends 35 of the bars. The bar 20 has a projection 36 bent over to provide a stop for the other bar 21. Likewise the bar 21 has a projection 37 bent over to provide a stop for the bar 20. This makes it possible for the bars to separate in the direction indicated in Figure 2, but they cannot be caused to separate in the opposite direction.

The bars are locked together by a fusible element 38 which is in the form of a small slug that can be dropped into the open end of the passage provided by the channels 33 and 34 while the bars 20 and 21 are held in alignment. When the slug is adjacent the end 35 the bars can be released and the tendency of the bars to swing apart will hold the slug in place. When the temperature in the bonnet 12 reaches a danger point, the slug 38 will melt. This will free the bars 20 and 21 from each other, and allow them to rotate to the dotted line position shown in Figure 2. The result is to lengthen the member 17 an amount sufficient to close the door 14.

Whenever the operator wants to restore the safety device to operative condition, he merely

brings the two bars 20 and 21 into alignment again, and drops a new slug 38 into the channel so as to lock the bars together.

Any low melting point metal may be used for the slug 38. The construction is such that immediately upon the slug melting to a point where the bars separate, the molten material of the slug runs out of the channels 33 and 34 so that these channels are not fouled, and new slugs can be inserted as often as is necessary. The shape of the slug and of the channel provided for it may of course be varied widely within the scope of my invention. Also more or less of the channel may be placed in either of the bars 20 or 21. Various other minor modifications may obviously be made without departing from the scope of my invention.

Having thus described my invention, I claim:

1. In a safety device of the character described, two bars having engaging faces, pivots on said bars for mounting them on a furnace, said bars having longitudinally running channels in their engaging faces providing an elongated passage between the bars when they are aligned, and fusible means in said passage holding the bars aligned.

2. In a safety device of the character described, two bars having engaging faces, pivots on said bars for mounting them on a furnace, said bars having longitudinally running channels in their engaging faces providing an elongated passage between the bars when they are aligned, and fusible means in said passage holding the bars aligned, said bars having overlapping portions limiting separation of their opposed faces while they are aligned.

3. In a safety device of the character described, two bars having engaging faces, pivots on said bars for mounting them on a furnace, said bars having longitudinally running channels in their engaging faces providing an elongated passage, open at one end and closed at the other, between the bars when they are aligned, and fusible means in said passage holding the bars aligned.

4. In a safety device of the character described, two bars having engaging faces, pivots on said bars for mounting them on a furnace, said bars having longitudinally running channels in their engaging faces, the channels opening to the edges of the bars at one end thereof and terminating short of the edges of the bars at the other end thereof, thereby providing an elongated passage between the bars when they are aligned, and fusible means in said passage holding the bars aligned.

5. In a safety device of the character described, two bars having engaging faces, pivots on said bars for mounting them on a furnace, said bars having longitudinally running channels in their engaging faces, the channels opening to the edges of the bars at one end thereof, and terminating short of the edges of the bars at the other end thereof, thereby providing an elongated passage between the bars when they are aligned, and a removable fusible slug in said passage holding the bars aligned.

MICHAEL S. CZOLGOSZ.
